[57] CLAIM

The ornamental design for character figure, as shown and described.

DESCRIPTION

FIG. 1 is a front view of a character figure showing our new design.

FIG. 2 is a right side view taken of FIG. 1, the left side being a mirror image thereof;

FIG. 3 is a rear view taken of FIG. 1;

FIG. 4 is a top view taken of FIG. 1; and,

FIG. 5 is a bottom view taken of FIG. 1.

The broken lines shown in FIG. 1 of the drawing are for illustrative purposes only and for no part of the claimed design.
